UNITED STATES PATENT OFFICE.

WILLIAM FEHLER, OF MOUNTAINVILLE, PENNSYLVANIA.

SAFETY-STOP FOR ELEVATORS.

SPECIFICATION forming part of Letters Patent No. 707,407, dated August 19, 1902.

Application filed April 10, 1902. Serial No. 102,278. (No model.)

To all whom it may concern:

Be it known that I, WILLIAM FEHLER, a citizen of the United States, residing at Mountainville, in the county of Lehigh and State 5 of Pennsylvania, have invented certain new and useful Improvements in Safety-Stops for Elevators; and I do declare the following to be a full, clear, and exact description of the invention, such as will enable others skilled 10 in the art to which it appertains to make and use the same.

This invention has relation to safety devices for elevators.

The object of the invention is to provide 15 simple, reliable, and effective means whereby in the event of breakage of the main hoisting-cable the guides at the sides of the elevator-shaft will be instantly engaged and the car prevented from falling.

20 With the above and other objects in view, which will readily appear as the nature of the invention is better understood, said invention consists in certain novel features of construction and combination and arrangement of 25 parts which will be hereinafter fully described, defined in the appended claims, and illustrated in the accompanying drawings, in which—

Figure 1 is a sectional elevation showing 30 the application and normal position of the parts of the invention. Fig. 2 is a similar view illustrating the action of the safety devices when the hoisting-rope breaks.

Referring to the drawings, the numeral 1 35 represents the elevator-shaft, provided with the guides 2, having toothed racks 3, and 4 is the car or cage, suspended from the hoisting-cable 5. The cable 5 is connected to a head or cross-bar 6, connected to tie-bolts 7, which 40 project downward through and below the car. Slidably mounted on the lower projecting ends of these bolts is a frame 8, carrying below the car spur gear-wheels 9, which mesh 45 with the racks 3. These gears are slightly spread apart, and adapted to come between them is a wedge 10, fixed to the bottom of the car.

The normal position of the parts when the car is suspended from the hoisting-cable 5 is

shown in Fig. 1, from which it will be seen 50 that the wedge 10 is held elevated, so that it does not come into engagement with the gear-wheels 9. If, however, the hoisting-cable 5 should break, the downward movement of the car would cause the wedge 10 to take the 55 position shown in Fig. 2, in which said wedge locks the gears 9 against movement, whereby the gears and racks would hold the car supported and prevent it from falling down the shaft. As the car is wholly unsupported upon 60 the breakage of the cable 5, while the downward movement of the frame 8 is retarded by the friction of the gearing, it will be obvious that the car will have a quicker initial fall, and that thereby the wedge 10 will be brought 65 into interlocking engagement with the gears 9, bringing both the car and frame to a stop.

From the foregoing description, taken in connection with the accompanying drawings, it is thought that the construction, mode of 70 operation, and advantages of my improved safety device for elevators will be readily apparent without requiring a more extended explanation.

Various changes in the form, proportion, 75 and the minor details of construction may be resorted to without departing from the principle or sacrificing any of the advantages of this invention.

Having thus described my invention, what 80 I claim as new, and desire to secure by Letters Patent, is—

1. In a safety-stop for elevators, the combination of toothed guides, a frame carrying gear-wheels engaging the guides, a car or cage 85 slidably connected to said frame, and a wedge upon the car adapted to come between and lock the gear-wheels against rotation upon a downward movement of the car when the hoisting-cable breaks, substantially as and 90 for the purpose set forth.

2. In a safety-stop for elevators, the combination of toothed guides, a car, tie-bolts connected to the car and projecting downward therefrom and having stops at their 95 lower ends, a frame in which said bolts are fitted to slide, the upward sliding movement of the bolts being limited by said stops, gear-

wheels carried by the frame and engaging the toothed guides, and a wedge fixed to the bottom of the car and adapted to come between and lock the gear-wheels against rotation upon a downward movement of the car when the hoisting-cable breaks, substantially as specified.

In testimony whereof I have hereunto set my hand in presence of two subscribing witnesses.

WILLIAM FEHLER.

Witnesses:

W. R. MOSER,
MORGAN PERSON.
